(57) **CLAIM**

The ornamental design for a blade for garden tool, as shown and described.

DESCRIPTION

FIG. 1 is a front view of a blade for garden tool made in accordance with my new design;
FIG. 2 is top plan view thereof;
FIG. 3 is a bottom view thereof;
FIG. 4 is a back view thereof;
FIG. 5 is a left side view thereof;
FIG. 6 is a right side view thereof;
FIG. 7 is a left side top perspective view thereof;
FIG. 8 is a right side bottom perspective view thereof;
FIG. 9 is a left side bottom perspective view thereof; and,
FIG. 10 is a right side bottom perspective view, shown as assembled to a tool handle.
Broken lines as shown are intended to show the design in a use environment, and in which the parts having broken lines do not form a part of the claimed design.

1 Claim, 10 Drawing Sheets
